UNITED STATES PATENT OFFICE.

HENRY G. WEATHERILL, OF ELGIN, ILLINOIS.

WHIP-HOLDER.

No. 909,718.

Specification of Letters Patent.

Patented Jan. 12, 1909.

Application filed August 6, 1908. Serial No. 427,331.

To all whom it may concern:

Be it known that I, HENRY G. WEATHERILL, citizen of the United States, residing at Elgin, in the county of Kane and State 5 of Illinois, have invented certain new and useful Improvements in Whip-Holders; and I do hereby declare the following to be a full, clear, and exact description of the invention, such as will enable others skilled in 10 the art to which it appertains to make and use the same.

My invention relates to whip-holders or hangers especially designed to be secured to vehicle tops and adapted to support a whip 15 in convenient position.

It has for its object to provide a simple device of this nature which being held in position by frictional contact may be quickly and readily adjusted and removed from its 20 position on the vehicle top.

A further object is to provide for holding the whip more securely when engaged with the holder so that there is less danger of said whip becoming disengaged and falling 25 out of the vehicle than there is when similar devices heretofore patented or used are employed.

The invention consists of a resilient clip, preferably made of bent wire and adapted 30 to be frictionally engaged with one of the locking levers of a buggy top or any suitably arranged rod or bar in any other vehicle top, said clip having an upwardly inclined extension at one side which is formed 35 into two resilient arms, leaving a V-shaped slot between them into which the lash end of a whip may be introduced and drawn downwardly until it is firmly clamped between said arms below the knot of said lash.

40 The invention further consists in the features of construction and combinations of parts hereinafter described and specified in the claims.

In the accompanying drawings, illustrating 45 the preferred embodiment of my invention: Figure 1 is a broken view of a portion of a buggy top showing my holder applied thereto and a whip supported by said holder. Figs. 2 and 3 are enlarged front and edge 50 views respectively of the holder alone, and Figs. 4 and 5 are similar views of a modified construction of holder which is made of sheet metal instead of wire.

55 Referring first to Figs. 1, 2 and 3, of the drawing, my holder, as therein illustrated,

is made of a piece of resilient wire which is first bent upon itself at the middle and then bent into shape as will be now explained.

The two strands of wire are bent at the same time to form a clip 1 having a restricted opening 2 through which the supporting rod 3 of the buggy top is forced when the holder is put in place. At one side of said opening the middle bent portion or loop of the wire is turned outwardly 60 as at 4 to guide the rod 3 through the opening 2 when the holder is pressed upon the upper edge of said rod. At the other side of the opening the strands of wire are also bent outwardly for the same purpose and in 65 addition are bent upwardly and inclined outwardly to form the resilient clamping arms 5. Said arms are fashioned by bending each of the two strands of wire upon itself and toward one another, leaving a V-shaped slot 70 6 between them. The extremities of the wire are interlocked in some suitable manner such as by being looped through one another as illustrated at 7.

Referring to Figs. 4 and 5, the holder is 80 there shown made of a single piece of resilient sheet metal which is bent to form the clip 1^a having the restricted opening 2^a, and otherwise fashioned to correspond to the shape of the wire holder shown in Figs. 1, 85 2 and 3. The end of the metal at one side of the clip is bent outwardly as at 3^a to form a guide while at the other side of said opening the metal is bent upwardly and outwardly as at 4^a. In the latter portion a V-shaped slot 5^a is cut leaving two arms 6^a between which the whip may be inserted and held as previously explained. It will be noted that the part 4^a is spaced away from the adjacent side of the clip leaving plenty 90 of room in which the knot of the lash of the whip may rest when said whip is hung upon the holder so that there is no danger of the 95 whip working loose and falling out.

It will be observed that because of the 100 shape of the clip, my holder may be quickly and firmly secured by simply forcing it on a supporting rod. While I have only illustrated the holder as applied to a vehicle top, it is evident that it may also be used in a 105 stable or store for supporting whips when not in use or when on exhibition. I am aware that changes may be made in the details of construction of my device without departing from the spirit or sacrificing the 110

advantages of my invention. I therefore reserve the right to make such alterations as fairly fall within the scope of my invention.

I claim:

- 5 1. A whip-holder made of resilient wire bent at the middle upon itself forming two side by side strands, said doubled wire being bent to form a clip having a restricted opening and converging sides whereby it may be forced upon a supporting rod and retained thereon by frictional contact, thence bent upwardly and outwardly at one side of said opening, the two strands being then bent downward upon themselves and towards one another with their extremities overlapped, 15 all for the purposes specified.
- 15 2. A whip-holder made of resilient wire

bent at the middle upon itself forming two side by side strands, said doubled wire being bent to form a clip having a restricted opening and converging sides whereby it may be forced upon a supporting rod and retained thereon by frictional contact, thence bent upwardly and outwardly at one side of said opening, the two strands being then bent downward upon themselves and towards one another, with their extremities interlocked all for the purposes specified.

In testimony whereof, I affix my signature, in presence of two witnesses.

HENRY G. WEATHERILL.
